UNITED STATES PATENT OFFICE.

THOMAS WARING, OF CAMDEN, NEW JERSEY.

PENCIL-SHARPENER.

SPECIFICATION forming part of Letters Patent No. 573,731, dated December 22, 1896.

Application filed October 16, 1895. Serial No. 565,882. (No model.)

To all whom it may concern:

Be it known that I, THOMAS WARING, a citizen of the United States, residing in Camden, New Jersey, have invented certain Improvements in Pencil-Sharpener, of which the following is a specification.

The object of my invention is to provide a simple and efficient form of pencil-sharpening device whereby scattering of the chips or shavings and soiling of the fingers are prevented and facilities are afforded for properly governing the depth of cut, also for properly pointing the lead after the wood has been shaved down around the same and for readily sharpening the knife when it becomes dull, the device being so constructed that the knife is prevented from acting upon the lead in such manner as to break the same while paring the wood, and the parts being so arranged that the power of the hand which manipulates the knife can be exerted to the best advantage and so as to have the knife under perfect control.

In the accompanying drawings, Figure 1 is a perspective view of my improved pencil-sharpening device, illustrating the manner of its use. Fig. 2 is a longitudinal section of the device. Fig. 3 is a transverse section on the line 3 3, Fig. 2. Fig. 4 is a transverse section on the line 4 4, Fig. 2. Fig. 5 is a transverse section on the line 5 5, Fig. 2. Fig. 6 is a transverse section on the line 6 6, Fig. 2; and Fig. 7 is a perspective view of the pencil-supporting block.

35 A represents a box having hinged lid A', said box being cut away at one side for the introduction of the pencil to be sharpened and having one of its ends reduced in height, so as to permit of the use of a knife-blade B with projecting external handle B'. On that side of the box which is cut away for receiving the pencil is a block D, with inclined or beveled inner edge a, in which are two tapering recesses x x', as shown in Fig. 7, the recess x being deeper than the recess x' and extending from top to bottom of the block D, while the shallow recess x' is shorter. These recesses constitute an inclined pencil-supporting bed.

50 The block D may be of hard wood, metal, or other available material and is suitably secured upon an inwardly-projecting table or

bed D' at the front of the box, said table or bed being preferably wider than the base of the block D, so as to form a projecting shoulder or flange d at the base of said block, although, if desired, this shoulder may only be formed at the point where the pencil is supported.

At its inner end the knife-blade B is snugly fitted into a clip F, which is pivoted to a stud f, projecting into the box from one side of the same near one end, the pivot end of the clip being flanked by washers g, which, however, as shown in Fig. 5, do not closely confine said pivot end of the clip, which is thus free to tilt or twist on the pivot-stud to an extent limited by a guide-loop G, which projects upward from the bottom of the box and is inclined slightly outward from bottom to top, as shown in Fig. 6, this guide-loop embracing the clip F, so as to determine the general direction of travel of the inner end of the knife-blade without, however, preventing such slight change of lateral position or angle of the same as is necessary to govern the depth of cut which is being made, this slight change of lateral position or angle being dependent upon the comparative looseness of fit of the clip F in the guide-loop and upon the slight amount of resiliency possessed by the latter. Some of the features of my invention are, however, applicable to a sharpener, in which the knife has no lateral freedom, but vibrates in a fixed plane.

In using the device the end of the pencil is first inserted in the deep recess x, as shown in Fig. 4, and the wood is gradually pared away by vibrating the knife B and turning the pencil as the knife acts upon the same, the depth or shallowness of the cut being regulated by the slight change of angle or slight inward and outward lateral movement of the knife, which is permitted by the looseness of joint of the pivot-clip and the slight lateral freedom of the guide G or of the clip in said guide. As the wood is pared away the cutting edge of the knife is prevented from acting on the projecting lead by the action of a guide-rib a' at the end of the inclined face of the block D, this guide-rib being such as to throw the cutting edge of the knife inward toward the center of the box before it can exert any injurious cutting or breaking effect upon the projecting lead or before any acting portion

of the knife-blade can come into contact with the face a of the block D, dulling of the cutting edge of the knife being thereby prevented. After the wood has been properly pared away 5 the pencil is shifted into the shallow recess x' and the projecting lead is thereby presented in proper position to be sharpened by the knife-blade B, as shown in Fig. 3.

The knife-blade has at the outer end a T-shaped handle B', as shown in Fig. 2, which can be readily grasped in the hand, as shown in Fig. 1, and which provides for a more perfect control of the blade than would a simple straight handle.

15 As the pencil occupies a position between the fulcrum upon which the knife-blade swings and the handle to which power is applied the force exerted upon the handle is multiplied by the leverage thus gained. Hence 20 the pressure of the hand upon the handle does not have to be so forcible as to interfere with the accurate control of the position of the cutting-blade.

While the inner end of the knife-blade 25 might, if desired, be directly pivoted, I prefer in all cases to use the clip F, for the knife-blade B can then be readily withdrawn from said clip when it becomes necessary to sharpen the blade, and when so withdrawn it can be 30 sharpened upon an ordinary whetstone as readily as any ordinary knife.

For convenience the whetstone may, if desired, be let into the lid or other suitable portion of the box, as shown, for instance, at I 35 in Figs. 3 and 5.

When the box D is made of wood or other like material, I prefer to affix to the same a base J, of lead or other metal, which, by reason of its weight, serves to give stability to 40 the box A in order to prevent the same from being shaken or moved by the hand under the action of the knife, this weighted base also rendering the device available as a paper-weight. The wood chips or shavings and 45 the lead parings accumulate in the box and can be readily discharged therefrom when desired.

Having thus described my invention, I claim and desire to secure by Letters Patent—

1. A pencil-sharpening device consisting of a box or receptacle having a table or bed for the support of the pencil, and a pivoted paring-knife having a loose pivot-joint whereby a certain amount of lateral freedom of the 55 knife is permitted, substantially as specified.

2. A pencil-sharpening device consisting of a box or receptacle having a table or bed for the support of the pencil, a pivoted paring-knife having a loose pivot-joint whereby a 60 certain amount of lateral freedom of the knife is permitted, and a guide-loop serving to limit such lateral freedom, substantially as specified.

3. A pencil-sharpening device consisting of 65 a box or receptacle having a table or bed for the support of the pencil, and a vibrating knife pivoted so as to have a limited amount of lateral freedom, with a guard rib or projection serving to prevent the cutting edge 70 of the knife-blade from coming into contact with the supporting-bed, or breaking the lead when paring away the wood from around the same, substantially as specified.

4. A pencil-sharpening device consisting of 75 a box or receptacle having a table or bed for the support of the pencil, a pivoted clip, and a paring-knife engaging with said clip and detachable therefrom, substantially as specified.

5. A pencil-sharpening device consisting of 80 a box or receptacle having a table or bed for the support of the pencil, and a paring-knife pivoted so as to have a limited amount of lateral freedom having at its free end a T- shaped handle, substantially as specified.

6. A pencil-sharpening device consisting of a box or receptacle having a table or bed for the support of the pencil, a whetstone secured to the lid of the box, a clip pivoted to 90 the box, and a vibratable paring-knife engaging with but detachable from said pivoted clip, substantially as specified.

In testimony whereof I have signed my name to this specification in the presence of 95 two subscribing witnesses.

THOMAS WARING.
